DESIGN FOR A TIE DISPLAY TRAY

Bert E. Spies and Ernest W. Baskette,
Dallas, Tex.

Application June 3, 1946, Serial No. 130,363

Term of patent 14 years

(Cl. D80—9)

To all whom it may concern:

Be it known that we, Bert E. Spies and Ernest W. Baskette, both being citizens of the United States of America, residing at Dallas, in the county of Dallas and State of Texas, have invented a new, original, and ornamental Design for a Tie Display Tray, of which the following is a specification, reference being had to the accompanying drawing, forming part thereof.

In the drawing

Fig. 1 is a top plan view of a tie display tray, showing our new design.

Fig. 2 is a side elevational view of the tray; and

Fig. 3 is an end view of the tray taken from the left end of Fig. I.

We claim:

The ornamental design for a tie display tray, as shown.

BERT E. SPIES.
ERNEST W. BASKETTE.
